UNITED STATES PATENT OFFICE.

THOMAS L. McKEEN, OF EASTON, PENNSYLVANIA.

BUFFER FOR LOCOMOTIVE AND TENDER COUPLINGS.

1,074,445.

Specification of Letters Patent. Patented Sept. 30, 1913.

Application filed December 8, 1910. Serial No. 596,317.

To all whom it may concern:

Be it known that I, THOMAS L. McKEEN, a citizen of the United States, residing at Easton, in the county of Northampton and State of Pennsylvania, have invented a new and useful Improvement in Buffers for Locomotive and Tender Couplers, of which the following is a specification.

This invention relates more particularly to improvements in friction buffering devices for pivoted couplers of the kind which are used on tenders or on the pilots of locomotives.

The objects of this invention are to produce a strong and efficient friction buffering device of high capacity which is adapted to be secured on the end-sill of the locomotive pilot or tender in place of the base plates or brackets heretofore used for pivotally supporting the coupler, and which is so constructed that the bracket or casing containing the buffering mechanism is of substantially the same dimensions and occupies practically no more space than the ordinary base plates or brackets, also to improve the construction of buffering devices for couplers of this type in the respects hereinafter described and claimed.

In the accompanying drawings, consisting of two sheets: Figure 1 is a sectional plan of a buffering device embodying the invention, on line 1—1, Fig. 2. Fig. 2 is a front elevation thereof, partly in section, on line 2—2, Fig. 1. Fig. 3 is a transverse sectional elevation thereof in line 3—3, Fig. 1. Fig. 4 is a longitudinal sectional elevation thereof.

Like reference characters refer to like parts in the several figures.

A represents a casing or bracket which is adapted to be secured to a tender or to a locomotive pilot in any suitable manner, for example, by bolts or rivets passing through suitable holes *a* in the base plate of the bracket or casing. The bracket has an integral hollow middle portion forming a chamber B in which the friction devices of the drawbar are contained and which has an opening *b* in its outer or front wall through

which the friction devices can be inserted into the chamber B. The drawbar chamber is relatively short lengthwise of the locomotive or tender to accommodate itself to the limited amount of space available.

C represents a coupler, of any ordinary or any suitable type, which has a short shank *c*

that enters the opening *b* of the drawbar chamber B and is pivotally connected to the casing A so as to permit the coupler to swing sidewise and also to move lengthwise of the locomotive or tender. In the construction shown, the coupler is pivoted by means of a vertical pin *c'* which passes through the shank *c* and through longitudinal slots *c*² in upper and lower flanges *c*³ which project outwardly from the bracket A above and below the opening *b* of the drawbar chamber. The swinging movement of the coupler is limited by the flanged side-walls of the opening *b*.

D represents a wedge which is located in the middle portion of the drawbar chamber B so as to bear against the inner end of the coupler shank, and is provided with opposite vertical oblique side faces *d* which converge toward the inner portion of the drawbar chamber. The contacting faces of the coupler shank and wedge are preferably curved concentrically with the coupler pivot pin *c'*, which permits the swinging or pivotal motion of the coupler. The oblique side faces of the wedge bear against the corresponding oblique faces of two oppositely disposed friction blocks E which are arranged in the drawbar chamber at opposite sides of the wedge and are pressed against the wedge D by leaf springs F F arranged in the opposite ends of the drawbar chamber B. The coupler shank, when secured in place by the pivot pin *c'*, practically fills the opening *b* in the drawbar chamber and retains the friction devices in place in the chamber. The friction blocks E are held against inward movement by the inner wall of the drawbar chamber, and when the coupler is forced inwardly in buffering, the coupler shank forces the wedge D inwardly into the drawbar chamber and the inward movement of the wedge causes the friction blocks to move laterally away from each other, compressing the springs F. A wear plate *e* of hard metal is preferably placed between the inner wall of the drawbar chamber and the friction blocks to protect said wall from wear by the blocks.

Each of the leaf springs F F preferably consists of two sets of bowed spring plates arranged vertically with their concave faces toward each other and their convex faces bearing against the friction block and the side wall of the drawbar chamber. The leaf springs give a much greater resistance

than could be obtained with coil springs occupying the same amount of space, and by employing two oppositely arranged sets of spring plates for each spring, as described, 5 sufficient movement of the friction blocks is permitted to make the inclination of the faces of the friction and wedge blocks great enough to enable a relatively long travel of the coupler and insure the releasing of the 10 wedge, thereby obviating the necessity for an additional spring to release the wedge. Thus by the described construction and arrangement of the springs and friction blocks a friction mechanism is produced 15 which offers a gradually increasing resistance of high ultimate capacity to the movement of the coupler and enables a long travel of the coupler, while nevertheless the buffering mechanism is of such compact construction that it can be arranged in a casing or bracket which is of practically the same dimensions as, and can be substituted in the place of, the brackets or base plates which have heretofore been used for pivoted locomotive and tender couplers and which have no buffering mechanism. Furthermore, the 20 buffer consists of very few parts, is inexpensive to manufacture, easy to assemble, and is so constructed that the parts which are 25 subject to the severest wear can be easily replaced when worn out.

f represents wear plates which are placed between the leaf springs and the bottom wall of the drawbar chamber.

35 G G represent plates which are inserted through slots in the top wall of the drawbar chamber between the edges of the leaf springs and the outer wall of the chamber. These plates serve to close openings *g* in the 40 outer wall of the buffer chamber, through which the leaf springs are inserted into and removed from the drawbar chamber. The openings *g* enable broken spring plates to be removed and others inserted in their 45 place without dismantling the rest of the buffer.

I claim as my invention:

1. The combination of a casing having a chamber, a coupler having a short shank 50 pivotally connected to said casing to swing sidewise and to move inwardly relative to said chamber, a wedge in said chamber in rear of the pivotal connection of the shank

to the casing and which is adapted to be moved inwardly in the chamber by said shank, the inner end of the shank being located in front of said wedge and movable laterally relative thereto, friction blocks in said chamber at opposite sides of said wedge and adapted to be moved laterally by said wedge, and means in said chamber for opposing the movement of said friction blocks, substantially as set forth.

2. The combination of a casing having a chamber, a coupler having a shank pivotally connected to said casing to swing sidewise and to move inwardly relative to said chamber a wedge in said chamber in rear of the inner end of the shank and which is adapted to be moved inwardly in the chamber by the inward movement of the shank, the inner end of the shank being movable laterally relative to said wedge, friction blocks in said chamber at opposite sides of said wedge and adapted to be moved laterally by said wedge, and leaf springs arranged in the opposite ends of said chamber for opposing the movement of said friction blocks, substantially as set forth.

3. The combination of a casing having a drawbar chamber, a coupler having a shank which has a pin and slot connection with said casing whereby it is adapted to swing sidewise and move inwardly into said drawbar chamber, a wedge in said chamber against which the inner end of said drawbar bears and relatively to which the shank is adapted to move, said wedge being adapted to be moved inwardly by said drawbar, friction blocks arranged in said chamber at opposite sides of said wedge and adapted to be moved laterally by the inward movement of said wedge, and leaf springs arranged in an upright position between the walls of said chamber and said friction blocks, said springs being adapted to yield laterally and to oppose the lateral movement of said friction blocks, substantially as set forth.

Witness my hand, this 3rd day of December, 1910.

THOMAS L. MCKEEN.
